COMBINATION MAILING AND RETURN ENVELOPE
WITH PULL-OUT FOR POSTAL INSPECTION

Filed Sept. 15, 1952

UNITED STATES PATENT OFFICE

2,686,005

COMBINATION MAILING AND RETURN
ENVELOPE WITH PULL-OUT FOR
POSTAL INSPECTIONJerome Hyman, Denver, Colo., assignor to The
Rockmont Envelope Co., Denver, Colo.

Application September 15, 1952, Serial No. 309,640

1 Claim. (Cl. 229—73)

2

This invention relates to a mailing envelope, and has for its principal object the provision of an envelope formed from a single piece of paper which will provide in a single convenient unit an original mailing envelope, a letter which can be opened for postal inspection, and a sealed return envelope for the use of the addressee which cannot be opened for postal inspection.

Another object of the invention is to so construct the improved envelope that the unsealing of the tab for postal inspection on the original envelope, and the complete sealing of the tab on the return envelope, will be accomplished entirely automatically without any attention on the part of the user.

While the improved envelope is more particularly designed for the collection of accounts and the solicitation of funds, it is, of course, not limited to this particular use, but can be used for any purpose where it is desired to send out an enclosed unsealed printed notice and to provide a sealed return, prepaid envelope for use of the addressee.

Other objects and advantages reside in the detailed construction of the invention, which is designed for simplicity, economy and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 illustrates the paper blank from which the improved envelope is formed;

Fig. 2 is a face view of the envelope prepared for the first mailing; and

Fig. 3 is a similar view of the envelope as it would appear both before and after sealing for the return mailing.

The improved combined letter and return envelope is formed by forming a paper blank as illustrated in Fig. 1 and folding the blank to form, in combination, the mailing envelope of Fig. 2 and the return envelope of Fig. 3.

The blank is cut to form a back portion 10 joined along one side edge to a front portion 11 by means of a fold line 12. Two end tabs 13 and 14 extend the full width of the back portion 10 and are joined to the extremities thereof by means of fold lines 15. A return envelope flap 16 extends the full length of the other side edge of the front portion 10 and joins the latter on a fold line 17. The width of the end tabs 13 and 14 and

the width of the return envelope flap 16 are substantially similar. A letter sheet 18 is attached to and projects from the side of the return envelope flap 16 and is joined to the latter by a perforated tear line 19. The above six parts or portions comprise the complete envelope blank.

The back portion 10 and the tabs 13 and 14 are blank and the tabs taper to a less width at their free edges than at the fold lines 15. The front portion 11 also tapers to a less width at its free edge than at the fold line 12 and one of the free edge corners of the front portion is cut off at an angle of 45° to provide a cut back corner 20. A gummed or adhesive area 21 is applied transversely across the back of the front portion 11 adjacent one extremity thereof. A legend reading "Use this envelope—No stamp necessary" is imprinted on the front of the front portion adjacent the free edge thereof, as indicated at 35, and the usual "business reply, no postage permit" postal information is also imprinted on the front face thereof, as indicated at 22 and 23. An area is provided on the front face for the reception of the user's name and address as indicated at 24.

The return envelope flap 16 is imprinted with instructions such as "Enclose Check—Fold and Seal" as indicated at 25 and with arrows 26 indicating the line 17 to be folded. Substantially the entire area of the front or inner face of the flap 16 is provided with gum or adhesive 27. The outer face of the flap 16 is blank.

The letter sheet 18 may be imprinted with the letter head of the user as indicated at 28 and provided with a printed letter or space for a printed letter as indicated at 29. The letter sheet also carries one or more gummed or adhesive areas 30 adjacent the free edge thereof. The reverse side of the letter sheet 18 is provided with the return address of the user, as indicated at 31, with a statutory postal notice reading "Pull Out Here for Postal Inspection", as indicated at 32, with an addressee space, as indicated at 33, and with a postage stamp or postage stamp box 34.

The envelope is designed to be mailed to the addressee by second class mail, and to be returned by the addressee to the sender by prepaid first class mail.

The envelopes are furnished to the sender by the envelope company or printer with the two tabs 13 and 14 folded inwardly on the fold lines 15 against the front of the back portion 10 and with the front portion 11 folded over the two folded tabs 13 and 14. The tab 13 is permanently secured in place by the adhesive 22. The tab 14 is held in place by the pressure and friction of

3

the enfolded front 11. The envelopes are preferably furnished with the user's letter 29 imprinted on the letter sheet 18 and with the other printed matter, as indicated at 22, 23, 24, 25, 26, 28, 31 and 32.

The user simply moistens the gummed areas 30 and seals the letter sheet down over the front portion 11 and addresses the envelope to the addressee, as shown at 33, and affixes a stamp in the stamp box 34 and mails the envelope in the 10 condition of Fig. 2.

It will be noted that for postal inspection, the tab 14 can be easily pulled outwardly to the broken line position of Fig. 2. It will also be noted that the adhesive areas 30 are positioned so that they will not interfere with or damage the address 24 on the return envelope.

The addressee receives the envelope and tears the letter sheet 18 away from the front sheet 11 at the spots indicated in broken line at 30' in Fig. 3 and severs the letter sheet 18 from the return envelope flap 16 along the perforated line 19. The addressee's check or other enclosure is then placed between the front portion 11 and the back portion 10. The adhesive 27 is moistened and the return envelope flap is sealed down over the front portion 11, as indicated in broken line at 16' in Fig. 3.

It will be noted that when the flap 16 is moistened and forced down over the front portion 11, the adhesive 27 will attach the tab 14 fixedly in place, due to the cut-back corner 20, so that the tab 14 is permanently secured to both the flap 16 and the front portion 11 and can no longer be opened for postal inspection. Thus, a first 30 class return envelope is automatically formed and which is self-addressed to the user at 24, and which contains the usual "First Class—No Postage" permit at 22.

While the adhesive areas have been described 40 as the gummed, water-wettable-type, any other type of adhesive could, of course, be used, such as the "Scotch" or latex pressure-types of adhesives.

4

While a specific form of the improvement has been described and illustrated herein, it is to be understood that the same may be varied, within the scope of the appended claim, without departing from the spirit of the invention.

Having thus described the invention, what is claimed and desired secured by Letters Patent is:

A combined mailing envelope, return envelope comprising: a back portion; an end tab at each extremity of said back portion folded inwardly over the front face of the latter; a front portion joined along one side edge of said back portion and folded over said end tabs; an adhesive area securing said front portion to the first of said end tabs; the free edge corner of said front portion which overlies the second of said end tabs being cut away so as to expose an area of the second of said end tabs adjacent the other side edge of said back portion; a return envelope flap extending throughout the length of the other side edge of said back portion and being foldable over said front portion and over said end tabs; a second adhesive area on said return envelope flap extending lengthwise thereon substantially to the edges thereof and adapted to secure the latter to said front portion and to the exposed area of said second end tab; a letter sheet secured along the free edge of said return envelope flap and being separable therefrom, said letter sheet being adapted to fold forwardly over said front portion and to form a second front portion thereover; and means adjacent the free edge of said letter sheet for attaching said letter sheet to said front portion when folded thereover.
